UNITED STATES PATENT OFFICE

2,259,603

AUTOMATIC CALENDAR

Benjamin S. Balinski, Chicago, Ill.

Application April 18, 1939, Serial No. 268,632

9 Claims. (Cl. 40—112)

My invention relates to mechanical calendars, and more particularly to those intended to operate over long periods, and my main object is to provide a calendar of this kind which performs its functions over a lifetime without attention or resetting as long as motive energy is supplied to it.

A further object of the invention is to include in the novel calendar means to automatically adjust the readings for the dates of the shorter and longer months, as well as those affected by leap years.

Another object of the invention is to group the date carriers in a compact series in order to have the calendar take up as little room as possible consistent with a sufficient display of the readings.

An additional object of the invention is to provide a mechanism for the novel calendar which is mainly grouped at one end thereof and very compactly.

Another object of the invention is to render the calendar mechanism suitable for actuation by an ordinary time piece, such as a spring-wound or electric clock.

An important object of the invention is to provide a mechanism which is largely positive in action, contains few springs, and requires only occasional lubrication to keep in proper condition.

With the above objects in view, and any others which may suggest themselves from the description to follow, a better understanding of the invention may be had by reference to the accompanying drawings, in which—

Fig. 1 is an encased view of the calendar combined with a numerical clock;

Fig. 2 is a full-sized front elevation of the calendar and its mechanism;

Fig. 3 is a rear elevation;

Fig. 4 is a vertical longitudinal section through an axial plane;

Figs. 5 to 10 are, respectively, sections taken on the lines 5—5 to 10—10 of Fig. 2;

Fig. 11 is a fragmental repetition of the upper portion of Fig. 8, partly broken away;

Fig. 12 is a fragmental elevation of a date carrier in the normal position;

Fig. 13 is a similar view, showing a changing position of said carrier;

Fig. 14 is a mechanical detail showing a date control;

Fig. 15 is a mechanical detail showing a control for regular and leap year months;

Fig. 16 is another view showing the controls for months and date changes;

Fig. 17 is another detail showing the positions of certain controls for ordinary, shorter and leap year months;

Fig. 18 is a typical drive mechanism for the calendar; and

Fig. 19 is an elevation of a disk-type dial front for the calendar.

Primarily, the novel calendar is intended to be read horizontally. Thus, the day reading is first at the left, then the date reading, then the month, and finally the year. The readings are slightly above the center of the calendar mechanism, and the front 20 of the calendar casing 21 is formed with rectangular openings 22 to disclose a given date. Thus, the corresponding legends in Fig. 2 are alined to show this date. Since it is preferable to have the calendar actuated by a clock, as previously mentioned, the casing may combine the numerical clock 23 above the calendar zone, as shown in Fig. 1.

The legends of the calendar are carried by a series of drums centered successively on a fixed shaft 25 and carrying the legends on peripheral dial portion. Thus, the day drum is indicated at 26, the date drum at 30, the month drum at 40, the multiple-year drum at 45 and the single-year drum at 50. Fig. 4 shows the manner in which these drums are arranged on the shaft 25. A collar 25a on the latter retains the assembly against sliding motion. As a modification Fig. 19 shows a series of disks arranged as the drums, where a flat type of indicator is desired.

As seen in Fig. 4, the drum 50 is formed with a hub 51 which is freely mounted on the shaft 25 and terminates at its left-hand end with a disk 52. The drum 45 also has a very short hub 46a and a disk 47 projected therefrom, the disks 47 and 52 being separated by a spacing collar 48.

The drum 40 is also formed with a hub 41 which is reduced as a long tube 42 to render the drum freely mounted on the shaft 25. The left-hand extremity of the tube 42 carries a large ratchet disk 43.

The drum 30 is formed with a hub 31 which is reduced to form a tube 42, which is freely mounted on the tube 42 and carries a ratchet disk 33 near its left-hand end, such end being extended with a radial arm 34. The hubs 31 and 41 are spaced by a long collar 34a.

The tube 32 receives a freely mounted tube 56 which carries a sector gear 57 near its left-hand

end, from which projects a radial arm 58 rigidly connected to the gear 57 by a pin 59.

The drum 26 is formed with a tubular hub 27 which freely encircles the tube 56 and carries a relatively small ratchet disk 28 at its left-hand end.

It is understood that the drums turn periodically to display the successive readings thereon, and the character of the mechanism requires that some turn in opposite directions from the others. According to the markings in Fig. 2, it is evident that the day drum 26 and date drum 30 move downwardly while the month-drum 40 and the year drums 45 and 50 move upwardly, arrows indicating these movements in a rotary direction in other views. The movements of the day and date drums 26 and 30 are instituted by the forward swing of the arm 58 to the extent where its companion sector gear 57 strikes a stop lug 60 carried by a cross rod 61 mounted in the lower part of the case 21; and the movement of the month and year drums 40, 45 and 50 is induced by the return swing of the said arm 58. This arm may thus be termed as the driver for the calendar mechanism, and its companion gear is provided for receiving energy from the clock or other external source previously mentioned, a suitable auxiliary gearing for this purpose being described in a later section. The design of the calendar mechanism requires that the arm should have and accomplish a sufficient stroke for fully attaining the functions during each of its movements, and it is therefore understood that the actuating unit will be required to impart the full or sufficient stroke to the arm in each direction. The return of the arm 58 is induced by a spring 58a leading to a fixed rod 64.

As indicated in Figs. 2 and 7, the drum 26 is spider-like with the peripheral legend-bearing portions 29 extended side-wise like wings. In order that these may come to the front in daily succession, the arm 58 is preferably actuated in a forward direction at or shortly after midnight. The disk 28 carried by the drum has the ratchet formation indicated at 29a in Fig. 7 and is formed with seven teeth. As noted in the same figure, the sector gear 57 has pivoted to it at 57a a pawl 57b which is urged against the periphery of the ratchet disk 28 by a spring 57d. Therefore, every forward stroke of the arm 58—that is, in the direction of the arrow in Fig. 7—will be calculated to rotate the disk 28 a sufficient distance to change the day reading in front. The disk 28 is of course controlled by a check pawl 57c which is pivoted on a rod 62 located in the rear of the casing. The spring 63 for the check pawl 57c is anchored on another rod to the rear of the rod 62 and numbered 64. The day readings are thus advanced and repeated without incident.

It has been mentioned that the drum 30 is directly connected with a ratchet disk 33, and the latter is therefore intended to take a partial turn each day, in the manner of the day ratchet disk 28, to change the date. The disk 33 is therefore formed with 31 peripheral teeth and is actuated by a large pawl 35 which is pivoted at its base on a side pin 36 carried by the arm 58 and is drawn toward the periphery of the disk 33 by a spring 37 secured between the pawl and the arm. These parts are shown in Fig. 6, and it is noted that the disk 33 also has a check pawl 38 underneath, the same being mounted on the rod 61 and with its spring 39 anchored on a pin 61a. It follows, therefore, that the disk 33 would be

impelled at the same time as the day disk 26 to change the date reading on the drum 30.

With the date drum 30 about the same diameter as the day drum 26 in order to lend the calendar assembly uniformity and compactness, it is evident that there will not be sufficient room on the periphery of the drum 30 to space the date carriers 39a in end-to-end succession. I therefore overlap them, as shown in Figs. 8 and 11, and cause the carrier for the previous date to move out of the way whereby to permit the carrier of the even date to fully show in the zone of display. This is done by causing the previous carrier to swing aside as the one for the even date descends into place. The means to accomplish this is simple. Thus, the drum 30 is composite in its plies as shown in Fig. 4 in order to accommodate pairs of spring blades 39b in rotary succession and extending radially a short distance beyond the periphery of the drum. The date carriers are flat plates 39c which—according to Fig. 2—are pivoted at their left-hand lower corners to the drum by means of pins 39d. These pass through square blocks 39e rigidly carried by the plates 39c, the blocks occupying the places between the extended portions of the spring blades 39b. Fig. 11 shows the carrier of the previous date in a position to descend upon a stop bracket 39f shown in Figs. 2 and 8, and rigidly secured to the rod 61. The carrier rests upon this bracket, but when the drum turns to lower the carrier, it is caused by the bracket to swing to the left, as indicated in Fig. 12, opposite corners of the block 39e then spreading the spring blades 39b. The further travel of the carrier causes it to snap into position a quarter turn beyond its original place and remain fixed by virtue of the pressure of the spring blades as shown in Figs. 13 and 2. Thus, the previous date reading is moved independently to a concealed position on each movement of the drum 30, so as to leave the even date reading in full view at the place of display. The next move of the drum causes the swung carrier to meet the upper end of a stop bracket 39g carried by the rod 61, so that the carrier is in this manner forced to swing back—in clock-wise direction—to its original position on the drum, this position, however, being below the display zone and maintaining the carrier in the concealed position.

It is recalled that the ratchet disk 43 is directly connected to the month drum 40. The teeth of the disk 43 are of course twelve in number, to agree with the peripheral portions 44 of the drum, which carry the readings. As was previously mentioned, the month drum is intended to rotate in the opposite direction from the day and date drums, and it follows, therefore, that the teeth 45a of the disk 43 are pointed in a reverse direction, as shown in Fig. 5. In order that the disk 43 may be drawn the distance of a tooth each month, a hook pawl 46 is also mounted on the side pin 36 of the arm 58 and is intended to fall in front of a tooth 45a when the arm 58 has advanced the date disk 33 by means of the pawl 35 to a point where the reading is the first of the month. The peripheral notch in the date disk 33 in this instance is deeper than the others, as indicated at 33a in Figs. 6 and 16. The pawl 35 has thus taken a deeper fall. The head of the hook pawl 46 carries a side pin 46a below a finger 35a forwardly projected from the pawl 35, as shown in Fig. 6. It follows, therefore, that the fall of the pawl 35 draws with it the hook of the pawl 46 to deposit the same in front of the proper tooth of

the month disk 43, so that the return stroke of the arm 58 draws this disk through a partial turn in the direction indicated by the arrow in Fig. 5 or 16, raising the next month reading to the display zone. The hook pawl 46 is normally urged away from the side pin 36; as shown in Figs. 6 and 16. As noted in Fig. 5, the month disk 43 receives a check pawl 46b underneath, such pawl being pivoted on the rod 62 and urged upwardly by a spring 46c which bears against the rod 64. When the hook pawl 46 draws on the month disk 43 as far back as the arm 58 is calculated to recede, it might be assumed that the spring 46c will automatically urge the hook pawl to disengage the disk at the end of the stroke. Yet, it is possible that this will not occur because of the engaging hold of the pawl upon the disk, even at the end of the stroke. I have therefore formed the check pawl 46b for the disk 43 with a rounded cam point 46d whose influence as it snaps into the proper tooth notch of the disk is to very slightly urge the disk ahead, that is, slightly beyond the point to which it was drawn. This action will automatically free the hook of the pawl 46, so that the same yields to the influence of the spring 46c to swing away from the periphery of the disk 43.

It will be recalled that the ratchet disk 52 is carried by the single-year drum 50, and the disk is cut with as many teeth as there are peripheral reading divisions 50a on the said drum, namely ten, reading from 1 to 0. When the month drum 40 has gone around once, it acts to shift the year drum 50 a sufficient distance to display the next figure. Accordingly, the month drum 40 carries a pin 53 which is adapted to meet a side lug 54 when the drum 40 rotates in the direction indicated by the arrow in Fig. 9. The lug 54 is carried by a bracket 55 pivoted on the rod 62 at its lower end. To the upper end of the bracket 55 is pivoted a lever 55k, this lever extending below the pivot 57k to be connected with its lower end to a stationary arm 65 by a draw spring 66. The arm 65 is fast on the rod 62 and carries a lateral stop pin 67 for the bracket 55. The upper portion of the lever 55k carries a cross-pin 68, one of whose sections seats in one of the tooth notches 52a of the ratchet disk 52. Thus, as the side pin 53 of the month drum continues to impinge on the side lug 54 of the bracket 55, the latter acts through the lever 55k to pull down on the disk 52 a suitable distance to occasion the change in the single year drum 50 previously mentioned.

The movement just described serves to rotate the year drum 50 one-revolution every ten years, and this movement is employed to act on the multiple-year-drum 45 to give the same a partial turn to secure the even ten-year numbers, such as 10, 20, 30, etc. Accordingly, one tooth notch 52b of the ratchet disk 52 is deeper than the other nine, as shown in Fig. 9. Ordinarily, the motions of the lever 55k and cross-pin 68 do not affect the ratchet disk 47, as the latter is of somewhat smaller diameter than the disk 52; so that the corresponding portion of the pin 68 simply rides above the periphery of the disk 47. However, when the 10-year change is to be made, the cross-pin 68 falls into the deep notch 52b and, at the same time into the companion notch of the disk 47. The downward movement of the lever 56 therefore draws on both of the disks, accomplishing the display of one of the even 10-year readings mentioned. It is thus apparent that, with the readings 1 to 0 also carried by

the 10-year drum 45, the calendar is capable of displaying readings from the year '01 to the year '99 which is over a period so long as to be well beyond the average span of life.

It is evident that a calendar of the type herein described must provide adjusting means for months which have less than 31 days. Thus, April, June, September and November have 30 days; leap-year February has 29 days and ordinary February 28 days. This circumstance affects the date-drum, since the date must change to the 1st of the next month before the current month is allowed to run 31 days. In the present calendar mechanism I cause the date-drum to be drawn through two steps when the month ends with the 30th day, so that the next date in view will be the 1st of the following month. Likewise, I cause the drum to be drawn through three steps at the end of a 29-day month and through four steps at the end of a 28-day month, whereby to skip the non-existent dates.

In accordance with the above plan, an element is provided alongside the date disk 33 which controls the distance in the advance of the feed pawl 35 at which such pawl engages the disk periphery. The element referred to is a sector plate 10 pivoted on the main shaft 25 and defining a peripheral cam 70a. It will be noted in Figs. 14 and 16 that this cam takes a deep fall 70b at a frontal point. The pawl 35 is sufficiently wide to travel over both the date disk 33 and the cam 70a, as appears in Fig. 3. Ordinarily, one tooth of the date disk occurs in front of the cam fall 70b, so that the advance of the pawl 35 a short distance farther secures the partial turn of the disk through one date. It will now be apparent from Fig. 14 or 16 that if the sector plate 10 is swung a short distance in a clock-wise direction, another date tooth will be exposed frontal of the cam fall 70b, so that on the advance the pawl 35 will drop onto the date disk a tooth earlier and so serve to push the disk over the distance of two teeth before the pawl reaches the end of its advance. It follows, then, that the backing of the cam 10 still farther will accomplish a longer date feed for the pawl 35. As a matter of fact, the tendency to retract the cam in the manner just mentioned is always present by the pull of a spring 71 upon the sector plate 10 toward a fixed bracket 72 carried by the side pin 61a, as seen in Fig. 6. In this manner the sector plate is drawn to a back limit formed by a detent 73 which engages a notch 74 near the lower end of the cam 70a, the detent being pivoted on the rod 62, as indicated in Figs. 14 and 16.

With the sector cam 70a described as a control for the engaging function of the pawl 35, it is necessary to determine how the various positions of the cam are fixed by the exceptional month values previously mentioned, that is, months having 30 days, 29 days and 28 days. These values are represented by a set of angle cams 75 carried by the month disk 43 at points near its periphery, as clearly shown in Fig. 5. Each angle cam is pivoted on a pin 76 carried by the disk; and the tail 75a of each cam is urged by a wire spring 77 in clock-wise direction to abut a stop pin 78, the spring extending from a pin 79 on the disk. Considering the direction of rotation of the disk 43, it is seen that each angle cam 75 and its tail 75a recede inclinedly from the pivot point 76.

The angle cams 75 are five in number, four representing the 30-day months and the fifth the 29-day and the 28-day Februaries. Behind

the series of angle cams is a curved arm 80 which is pivoted on the rod 62 jointly with the detent 73, by means of a common hub 80a, indicated in Figs. 3, 5 and 14. Below the pivot 62 the arm 80 is drawn by a spring 81 to the cross-rod 64. The upper portion of the arm 80 is deflected forwardly to form a finger 80b which is directly in the path of each angle cam 75 when the disk 43 takes a rotary movement as shown in Fig. 5. Thus, a given angle cam changes from the position denoted by full lines in Fig. 17 to either of the three positions indicated by dotted lines in the same figure. The four angle cams at the lower right and upper left in Fig. 5 represent the 30-day months, and it may be assumed that these angle cams occur in the uppermost dotted line position in Fig. 17 as each in turn gets under the finger 80b.

It was stated in an early section that the tube 32 extended from the date drum 30 carries a radial arm 34, and it may now be specified that this arm is within the circle of the angle cams 75. The arm is tapered to a rounded point, as indicated at 34a, which travels close to the free ends of the angle cam tails 75a as the date drum moves from day to day. However, when one of these cams is swung to the dotted line position of Fig. 14, it is seen that its tail projects into the path of the arm 34. The progress of the arm induces the clock-wise rotation of the angle cam to the extent of pushing the arm 80 away sufficiently to withdraw the detent 73 from the notch 74 of the sector cam 70a. The sector plate, now released, is drawn by the spring 71 until a side pin 81 strikes the inner side of the angle cam tail 75a. This means that the sector cam 70a has moved over through the space of an extra tooth on the date disk 33, permitting the pawl 35 to engage the said disk one tooth earlier on the advance and move the disk over through two dates. The arm 34 is so positioned in relation to the array of dates on the drum 30 that these two dates are the 30th and 31st. Consequently, for a 30-day month the 30th and 31st date readings are moved over together when the first reading of the next month is to be exposed.

The remaining angle cam 75—at the top right in Fig. 5—is intended to set the date drum for the 29-day and 28-day Februaries. The action in reference to this angle cam is precisely the same as in the previous instances, except that this cam occurs in the middle dotted line position of Fig. 17 when the 29-day month ends and in the bottom dotted line position when the 28-day month ends. These positions indicate that the tails of the respective angle cams are one and two steps farther from the approach of the side pin 81 shown in Fig. 14, and that the sector plate 70 will swing correspondingly farther on its release by the detent 73, offering increasing exposures of the periphery of the date disk 33 for the progressively earlier engagement of the pawl 35. It follows, therefore, that the 29th, 30th and 31st date readings will be moved over in unison at the end of a leap year February, and that the 28th, 29th, 30th and 31st date readings will be similarly moved at the end of an ordinary February.

The February angle cam is not directly secured to the disk 43, but is pivoted on a pin 76a which passes through a slot 43a in the disk 43 and is carried by the outer portion of an arm 82 pivoted on the main shaft 25 along the outer side of the disk 43, as indicated in Figs. 5 and 15. The disk 43 has an outwardly projecting fixed spindle 75

on which is journaled an integral assembly of a disk cam 84 and a spur gear 85. The cam 84 is in the plane of the arm 82 and ordinarily presents a circular periphery to the latter as indicated in Fig. 5, the arm being maintained as a follower against the cam periphery by a spring 86 (see Fig. 5) directed to a pin 87 carried by the plate 43. The cam has a flat peripheral portion 84a, and Fig. 15 shows the position of the arm 82 when it is opposite such portion. In such event, the related angle cam 75 is with its pivot in the upper part of the slot 43a; and when the cam 84 is in the position of Fig. 5, the angle cam is at the bottom of the slot. These positions correspond with the middle and lower dotted line positions of the angle cam in Fig. 17, the basic functions of these having been previously described.

The stationary shaft 25 carries a fixed spur pinion 88 in mesh with the gear 85. Considering that the month disk 43 undergoes one revolution a year, a ratio of 4 to 1 between the gear 85 and the pinion 88 will impart one revolution to the gear 85 every four years. The cam 84 is so arranged that its circular portion is opposite the arm 82 during three ordinary years and the flat peripheral portion 84a is so located during the fourth or leap year. Consequently, during the leap year the corresponding angle cam 75 will be at the height of the middle dotted illustration in Fig. 17 and change the end of the February reading on the 29th, whereas during the other three years the angle cam will be in the position of the lowermost dotted illustration in the same figure and change the said reading on the 28th.

It will be noted that the cam fall 70b is as deep as the special notch 33a of the date disk 33, the reason for this being to allow clearance for the entry of the pawl 35 into the notch 33a. This is apparent in Fig. 16, and it will be noted that to the left of the fall 70b the sector plate 70 has a ledge 70c followed by a stem 70d. The ledge is in front of the pawl 35 and even with the left-hand wall of the notch 33a when the parts are positioned as in Fig. 16 for the change of the month. As for the stem 70d, it is ordinarily in spaced relation to the advanced position of the pawl 35. Thus, when the dates of a 31-day month are consecutively shifted, the pawl 35 rides at the level of the regular tooth notches of the disk 33. Now, when the pawl has advanced at a time where the detent 73 is withdrawn as previously described to release the sector plate 70 to the backing pull of the spring 71, the stem 70d of the sector plate immediately moves to meet the front of the pawl 35, and the retraction of the latter checks the sector plate from a too rapid or noisy return. On the advance of the pawl the deep notch 33a gives it access to the ledge 70c of the sector plate to re-set the pawl in the foremost position.

The auxiliary gearing for driving the sector gear 57 will now be described. Fig. 18 shows an alarm or other special wheel 88a of the clock or other time device which turns one revolution at a given clock time, which is of course every twelve hours. The wheel 88a carries a swiveled radius block 89 which is slidable in a slot 90 in one arm 91 of a bell crank 92 which is pivoted at the angle on a stationary shaft 93. A pawl 94 extends pivotally from the other arm of the bell crank to the peripheries of a single-tooth ratchet gear sector 95 and a multiple-tooth ratchet disk 96, these units being journaled alongside each other on a stationary shaft 97. The gear sector

95, is operatively connected through an intermediate pinion 98 to the sector gear 57. It is the function of the special wheel 88a to swing the bell crank 92 a given distance in the counter-clockwise direction and back with each revolution, this having the effect—through the pawl 94—to turn the disk 96 counter-clockwise the distance of one tooth, the disk remaining or being suitably held still on the return of the pawl. The tooth of the gear sector 95 receives the pawl at the same time when the sector gear 57 is in the idle or rear position, so that this gear is advanced through its stroke by the action of the pawl 94. The time at which the special wheel 88a induces the above movements is set to occur shortly after midnight, or at any time during the night, to procure the necessary calendar advance for the next day. As a matter of example, the action may occur at 12:01 a. m. Now, when the clock wheel 88a is again actuated at 12:01 p. m.—its impulse to the calendar must not occur, as that would advance the calendar again—at noon. Alternating teeth of the ratchet disk 96 therefore occur at a greater radius than the gear sector tooth, so that when the disk is again turned the pawl 94 will be higher and out of reach of the gear sector tooth. The above mechanism has been described as a preferable one, although any other which serves the ultimate purpose may be employed. It is noted that the pawl 94 could have been placed to act directly on the sector gear 57, but this would unduly complicate the calendar mechanism. Therefore, the interposition of the pinion 98 places the control high and out of the way or in a manner to be designed as a separate or auxiliary unit. It is also possible to actuate the calendar mechanism from a remote source, that is, where the clock or timer is elsewhere and transmits its impulse electrically to a magnet or solenoid whose armature is the actuator. It is feasible in this manner to control a plurality of calendars in different rooms, offices or parts of a building from a centralized source, providing an automatic calendar service.

It will be evident from the above description that a calendar is provided which is fully automatic over the span of a lifetime. With electric current available in all communities in one form or another, the supply of the necessary energy is easily available for the mechanism which operates the calendar, whether the same is a clock incorporated in the calendar housing or simply an electric timing device auxiliary to the calendar mechanism. Considering its functions, the mechanism is quite simple and of a nature to be compactly designed so that it may occupy a minimum of room. Further, parts of the mechanism have a limited operation but once a day and other parts more seldom, so that wear of the mechanism is so slight as to be negligible. Further, it is a simple matter to approach the drums from the rear, to re-set them if necessary, by withdrawing the controls thereof momentarily. Finally, it will be obvious that the calendar can be built by modern manufacturing methods to sell at a reasonable figure.

While I have described the novel calendar along specific lines, various minor changes and refinements may be made therein without departing from its principle, and I consider all such changes and refinements as coming within the scope and spirit of the appended claims.

I claim:

1. In an automatic calendar, a date unit having 31 teeth representative of 31-day months, a

pawl movable daily relative to said teeth to normally advance the unit a step each day, a month unit, means actuated on the last day-of-the-month by the date unit to advance the month unit a step in the rotation of a calendar month, and a control governed by the positions of the month unit to accelerate the date unit at the end of months of less than 31 days a number of steps equal to the difference of days in such months, dates-of-the-month and months-of-the-year dials carried by said date and month units and disposing readings in rotation in regions of display, said pawl having an advancing movement over several teeth, said control including a cam alongside the teeth and of a height to normally withhold the pawl from engaging the teeth until the final portion of its advance where the pawl moves the date unit one tooth, means to retain the cam in its normal position, means to retract the cam when the retaining means is released, elements carried by the month unit for the release of the retaining means at points corresponding to the display positions of months less than 31 days, and an actuator carried by the date unit and effective on said elements when the last days of such months are on display to release the retaining means and allow the cam to be retracted a distance exposing to the pawl a number of said teeth equal to the difference of days in the shorter months from the 31 day months.

2. In an automatic calendar, a date unit having 31 teeth representative of 31-day months, a pawl movable daily relative to said teeth to normally advance the unit a step each day, a month unit, means actuated on the last day-of-the-month by the date unit to advance the month unit a step in the rotation of a calendar month, and a control governed by the positions of the month unit to accelerate the date unit at the end of months of less than 31 days a number of steps equal to the difference of days in such months, dates-of-the-month and months-of-the-year dials carried by said date and month units and disposing readings in rotation in regions of display, said pawl having an advancing movement over several teeth, said control including a cam alongside the teeth and of a height to normally withhold the pawl from engaging the teeth until the final portion of its advance where the pawl moves the date unit one tooth, means to retain the cam in its normal position, means to retract the cam when the retaining means is released, elements carried by the month unit for the release of the retaining means at points corresponding to the display positions of months less than 31 days, an actuator carried by the date unit, and a stop carried by the cam and effective when meeting the releasing one of said elements to determine the extent to which the cam becomes retracted.

3. In an automatic calendar, a date unit having 31 teeth representative of 31-day months, a pawl movable daily relative to said teeth to normally advance the unit a step each day, a month unit, means actuated on the last day-of-the-month by the date unit to advance the month unit a step in the rotation of a calendar month, and a control governed by the positions of the month unit to accelerate the date unit at the end of months of less than 31 days a number of steps equal to the difference of days in such months, dates-of-the-month and months-of-the-year dials carried by said date and month units and disposing readings in rotation in regions of display, said pawl having an advancing movement over several teeth, said control including a cam

alongside the teeth and of a height to normally withhold the pawl from engaging the teeth until the final portion of its advance where the pawl moves the date unit one tooth, means to retain the cam in its normal position, means to retract the cam when the retaining means is released, elements carried by the month unit for the release of the retaining means at points corresponding to the display positions of months less than 31 days, an actuator carried by the date unit, means carried by the month unit independently positioning the one of said elements relating to February dates, and a connection effective by the movement of the month unit to shift said element to vary the last-day display of February dates from the regular 28th to the leap-year 29th.

4. In a calendar mechanism, a ratchet date-disk effective on rotation to display readings of dates of the month, a pawl reciprocable over the disk periphery and effective on the advance to move the disk for daily displays to the end of the month, a companion reverse-ratchet month-disk effective on step-by-step rotation to display readings of months of the year, the first-day tooth of the date-disk defining a deep notch, a second pawl reciprocable over the month disk periphery and effective on retraction to move such disk in said rotation, and means between the pawls to lower the second one into engagement with the month-disk when the first pawl falls into said notch.

5. In a calendar mechanism, a date disk having 31 teeth representative of 31-day months, a pawl adapted to be advanced daily relative to said teeth to normally turn the disk a step each day, a month disk, means actuated on the last day-of-the-month by the date disk to advance the month disk a step in the rotation of a calendar month, a cam alongside the periphery of the date disk and barring said pawl from engaging the date disk before becoming effective for said step, means influencing the cam to move in a direction opposite to the rotation of the date disk, a detent checking the movement of the cam in said direction, an extension of the detent alongside the month disk, rockable units carried by the latter at points corresponding to months shorter than 31 days and in the path of said extension to be deflected thereby when intercepted, an arm carried by the date disk and effective to rock a deflected one of said units at a point consistent with the position of the pawl for the premature engagement with the date disk to advance it

through the non-existent dates of the particular shorter months, the rocking of said deflected unit crowding the extension to disengage the detent from the cam and permit the same to move, and a projection carried by the cam to meet said unit and stop the cam at a point to clear the pawl for said premature engagement.

5 6. The structure of claim 5, a false support for the February unit relative to the month disk, 10 and a second cam geared to the latter to rotate once in four years, the support being influenced by said second cam at the end of a leap-year February to move the related unit forward and affect said pawl accordingly.

15 7. The structure of claim 5, a follower arm pivoted co-axially with the month disk, a stationary axle for the latter, a pinion fast on the axle, a planetary gear carried by the month disk in mesh with the pinion at a 4 to 1 ratio, and a 20 cam carried by the gear with a dwell to maintain the related unit in a position to affect said pawl at the end of a regular February and with a fall to move such unit forward at the end of a leap-year February and affect the pawl accordingly.

25 8. In a calendar mechanism, a date drum having peripheral sections for step-by-step daily display, said sections overlapping in rotary sequence to permit as many as 31 sections to be grouped compactly, and means operative when a given date section is on display to draw aside the next overlapping section, whereby to leave the displayed one in full view, the sections being pivoted at one of their corners to the drum, and said 30 means comprising an abutment in the motive path of the sections.

9. In a calendar mechanism, a date drum having peripheral sections for step-by-step daily display, said sections overlapping in rotary sequence 40 to permit as many as 31 sections to be grouped compactly, and means operative when a given date section is on display to draw aside the next overlapping section, whereby to leave the displayed one in full view, and other means to replace the section drawn aside into the series at a point beyond the zone of display, the sections being pivoted at one of their corners to the drum, and said other means being an abutment in the 45 motive path of the moved section and effective to swing it back to normal position on the movement of the drum.

BENJAMIN S. BALINSKI.
